UNITED STATES PATENT OFFICE

2,449,435

FORM SELECTOR FOR DENTURE PROSTHESIS

Winthrop C. Whittemore, Port Washington, N. Y., assignor to The Dentists' Supply Company of New York, New York, N. Y., a corporation of New York

Application February 1, 1946, Serial No. 644,866

9 Claims. (Cl. 32—71)

1

It is a generally accepted principle in denture prosthesis that normal cases show the existence of quite a definite relationship between the shape of a person's face and the form of his upper central incisor teeth. Thus a tapering face and a tapering central incisor go together, a squarish face goes with a square type central, an ovoid face with an ovoid central, and so on. It is also well recognized that in normal cases there is a proportionate size relationship between the face and tooth.

These principles have been utilized by the profession as general guides helpful in the selection of artificial teeth which will be suited best to the patient. A variety of devices have been invented with the objective of making the form comparisons and facial measurements believed essential in the practical application of the stated principles in the selection of teeth according to faces. The present invention relates to this general class of device, to which the art has referred variously as selection gauges, form finders, or tooth selectors.

It is an object of my invention to provide a form selector which is simpler and easier to use, and which is of more universal application than instruments known or used heretofore. As one example of the instruments invented in the past, I make reference to United States Patent No. 1,378,527 which shows a gauge designed to be fitted to the patient's face for making form and size determinations. This type of instrument is rather cumbersome to handle and may be objectionable to the patient. It is one of the objects of my invention to provide an instrument which can be utilized for making both form determinations and size measurements without applying any scales or other devices directly to the patient's face.

As another example of the prior art, I cite United States Patent No. 1,469,893. With the type of tooth selector disclosed in that patent, form determinations could be made without applying a mechanism directly to the patient's face. However, direct determinations of form or size were impossible, for the operation of the instrument was based on trial and error. It has been a further object of my invention to provide a form selection instrument which not only avoids the necessity of fitting parts to the patient's face, but which affords direct and immediate determinations of both form and size without resort to time-consuming trial and error methods. Other objects and advantages will appear as the description proceeds.

In the drawings,

Fig. 1 is a side elevational view of an instrument embodying the invention in a preferred form.

Figs. 2 and 3 are enlarged detail sectional views

2

taken as shown at 2—2 and 3—3, respectively, in Fig. 1.

Fig. 4 is a detail view of the measuring transparency and its mounting.

Fig. 5 is a view of the instrument of Fig. 1, partly in vertical longitudinal section, showing how the instrument is assembled with the parts in telescoping relationship for compact storage or shipment.

Fig. 6 is a diagrammatic representation of a patient's face with superimposed coordinate guide lines as viewed through my instrument.

Figs. 7, 8 and 9 are diagrams showing the coordinate guide lines as viewed through my instrument, in relation to inverted outlines representative of typical central incisor teeth.

In its general arrangement, my instrument comprises an eye-piece 10, a transparency 11 having coordinate guide lines 12 thereon, and an arm 13 for spacing the eye-piece a predetermined distance from the patient's face. In use, the doctor places the tip of arm 13 opposite, or against the chin of his patient, holding the eye-piece approximately level while he sights through it with his patient's face centered on the coordinates of the transparency and takes his readings. To assist him in holding the instrument level, a plumb-bob 14 is arranged in position to be within his range of vision during sighting. In my preferred construction, this plumb-bob will flutter when the instrument is level, but stop fluttering when it is not.

The spacing, or sighting, arm 13 preferably is made in tubular sections 15, 16, 17 which can be nested together like the sections of a telescope for storage or shipment. These sections may be made of wood, metal, plastic resins or such other material as may be desired. I have found that a transparent molded plastic is well adapted for the purpose. In my preferred construction illustrated, the outside diameter of section 16 of the spacing arm is substantially equal to the inside diameter of section 15 and the outside diameter of section 17 is substantially equal to the inside diameter of section 16, so that each section will slide into the other and yet be tight enough to hold. Raised portions or collars 18, 19 on the sections 16 and 17 respectively form positioning stops for assembly. If desired, a slight taper may be formed on the outside of the tubular sections to the right of collars 18, 19 as viewed in Fig. 1, so that as the sections are pressed home, they will be tightly held. At the end of section 17 a rounded tip 20 is formed or attached.

The transparency 11 having the coordinate guide lines 12 is mounted in the line of sight of the eye-piece or telescope 10. The mounting may be interiorly or exteriorly of the telescope. For illustration I have shown the latter form of mounting, in which case the transparency is di-

rectly supported on the tubular section 15 as by means of a frame 21 fixed to a collar 22 which slides over the end of section 15 against a second, fixed, collar 23. The two collars are formed with complementary shoulders so as to provide a locking engagement at 24 which prevents turning of the transparency mounting relative to the section 15 of the spacing arm, thus preserving accurate alignment between the transparency and the eye-piece which is mounted on the same section of the spacing arm.

The coordinate lines 12 may be formed on the transparency by etching or otherwise, and the transparency itself may be formed of glass or transparent plastic. If the latter, it may be unnecessary to use a supporting frame, and the transparency and the collar 22 may be formed integrally.

The coordinate guide lines 12 comprise a series of parallel vertical and horizontal lines as shown in Fig. 4. I prefer that these lines be calibrated in relation to the magnification of the telescope 10, length of the arm 13, and the proportionate size relationship between the face and the tooth (generally considered to average 16:1), so as to give a direct reading of tooth width and length in millimeters based upon direct observation of the coordinate lines in relation to the height and width of the patient's face, as viewed in superimposed relationship. Thus in Fig. 4 the horizontal and vertical sets of numerals designate tooth width and length in millimeters. I have found it preferable to omit the horizontal lines between 1 and 6, except at the extreme sides of the grid. This makes observation of the patient's face easier. Also by arranging the vertical numbers 1, 6, 7, 8, 9, 10, 11, 12 at the center of the grid and 2, 3, 4, 5 at the side of the grid, reading is facilitated. Further to facilitate reading, the even numbered vertical parallels may be made slightly heavier than the odd numbered ones.

Fig. 6 gives an idea of what the observer sees when the form selector is aimed in the manner previously described. Vertical guide line 6 is used as a guide in centering the patient's face laterally. The zero horizontal or top of the grid is sighted at the normal hair-line of the patient. It will be observed that in this diagram the face measures 11 units from hair-line to chin, and is 10 minus 2, or 8, units wide. It is important to note that the hair at the side of the head must be disregarded in making the reading. Assuming calibration for direct reading of recommended tooth size in millimeters, this reading indicates selection of a central tooth measuring 11 mm. from gingival to incisal tip, and 8 mm. from mesial to distal at the widest part of the tooth. An idea of how the tooth size and form correspond can be obtained from a comparison of Fig. 6 with Fig. 7.

In Fig. 7 I have shown diagrammatically the approximate outline (inverted) of a "square" central incisor tooth superimposed on the grid. The tooth indicated by this outline is 11 by 8 mm. The size selection is indicated by the readings in Fig. 6. It will be observed that approximately from 1 to 6 vertical the sides of the tooth are approximately parallel and that from 6 to 11 vertical they curve broadly, so that the general form of the tooth is squarish or, in the parlance of dentistry, "square," just as the face shown in Fig. 6 would be described as square.

Other types of face and tooth forms are indicated diagrammatically in Figs. 8 and 9, again

superimposed on the grid. Fig. 8 shows what is known as the "square tapering" form and Fig. 9 a (full) "tapering" form. In the tapering form, the sides of the face and the tooth slope inwardly from approximately 1 to 11 vertical. In the square tapering form which, as the name indicates, is a combination of Figs. 7 and 9 forms, the sides are substantially parallel from about 1 to 5 or 6 vertical, and from 5 or 6 to 11 slope inwardly. It will be understood that the readings shown by these diagrams are illustrative only and will vary for different tooth sizes and will even vary somewhat as to form, although the representations shown may be considered as fairly typical as to form. It will also be understood that my invention is applicable to the determination and measurement of other forms and sizes than those selected for illustration and is adapted to show at a glance not only the size of tooth which is to be considered most suitable for a given patient, but also whether he is to be classified in type as "square," "tapering," "ovoid," "square tapering," or "reverse tapering," etc. The omission from the grid of the horizontal guide lines between 1 and 6, or of at least the central portion of these guide lines, is of assistance in determining type because in the square or square tapering type, the portions of the sides which are substantially parallel fall within the 1 to 6 readings for average tooth sizes, so the vertical lines are emphasized over this area of the grid, whereas coordinates comprising both vertical and horizontal lines are emphasized where the contour curves or slopes.

35 The sight or telescope 10 is mounted on section 15 of the sighting arm as by means of a tubular member 25. I prefer to make this member of transparent plastic although this is not essential. Near its lower end the member 25 is provided with a pair of opposed slots 26 through which extend the ends of a plate 27 pendulously supported by a rod 28 from a pivot such as may be provided by a hooked pin or rivet 29. The clearance between the plate 27 and the upper and lower edges of the slots 26 is such that when the line of sight, L. S., of the instrument departs substantially from the horizontal, the swing of the pendulum or plumb-bob 14 will bring the plate into engagement with the upper or lower sides of the slots, or one of them, and thus arrest movement of the bob. Also the clearance between the lateral sides of the slots 26 and the plate 27 is such that if the instrument is tilted to one side or the other, the plate will engage the sides of the slots or of one of them and arrest its motion. (In the drawings the clearance between the top, bottom and sides of the plate 27 and the sides of the slots 26 has been exaggerated for ease of illustration.) In manipulation the doctor places the tip 20 of arm 13 opposite or against the chin of his patient, holding the eye-piece and the horizontal guide lines of the transparency 11 level. So long as the instrument is held in this level position, the plumb-bob or pendulum 14 will flutter because of its lightness and sensitivity. However when the level is disturbed, either by tilting the instrument to one side or by tilting the telescope up or down from the horizontal, the bob will stop fluttering by reason of contact of the plate 27 with the sides of the slots 26 as described.

60 When in use the instrument is assembled in the manner described and as shown in Fig. 1. When not in use, it may be taken apart for storing in a box or drawer, or for shipment. The

sections 15, 16 and 17 may be separated and the transparency 11 removed from section 15. The three sections of the spacing arm may then be re-assembled in reversed relationship in the manner indicated in Fig. 5.

The terms and expressions which I have employed are used in a descriptive and not a limiting sense, and I have no intention of excluding such equivalents of the invention described, or of portions thereof, as fall within the purview of the claims.

I claim:

1. A form selector for denture prosthesis comprising a telescopic eye-piece, a transparency associated with the eye-piece having coordinate guide lines thereon, and an arm extending from the eye-piece substantially in the plane of the line of sight thereof for spacing the eye-piece from the face of a patient.

2. A form selector for denture prosthesis comprising a telescopic eye-piece, a transparency associated with the eye-piece having coordinate guide lines thereon, an arm extending from the eye-piece substantially in the plane of the line of sight thereof for spacing the eye-piece from the face of a patient, and means for indicating when the line of sight is level.

3. A form selector for denture prosthesis comprising a telescopic eye-piece mounted on a spacing arm extending in a direction substantially in the plane of the line of sight of the eye-piece, and a transparency mounted on the spacing arm forwardly of the eye-piece, the transparency having coordinate guide lines so arranged that when the eye-piece is directed toward the face of a patient the observer will see the coordinate guide lines superimposed on the patient's facial contour.

4. A form selector for denture prosthesis comprising a telescopic eye-piece mounted on a spacing arm extending in a direction substantially in the plane of the line of sight of the eye-piece, a transparency mounted on the spacing arm forwardly of the eye-piece, the transparency having coordinate guide lines so arranged that when the eye-piece is directed toward the face of a patient the observer will see the coordinate guide lines superimposed on the patient's facial contour, and a plumb-bob mounted in association with the spacing arm.

5. A form selector for denture prosthesis comprising a telescopic eye-piece mounted on a spacing arm extending in a direction substantially in the plane of the line of sight of the eye-piece, a transparency mounted on the spacing arm forwardly of the eye-piece, the transparency having coordinate guide lines so arranged that when the eye-piece is directed toward the face of a patient the observer will see the coordinate guide lines superimposed on the patient's facial contour, a plumb-bob mounted in association with the spacing arm, and means for arresting movement of the plumb-bob when the eye-piece is out of plumb whereby the observer can ascertain through free movement of the bob during facial measurement that his line of sight is correct.

6. A form selector and facial measurement device for denture prosthesis comprising a telescopic eyepiece, a transparency associated therewith and a means for maintaining an accurate, predetermined spacing between the eyepiece and the face of the patient; the said transparency carrying a series of coordinated guide lines calibrated in terms of tooth dimensions and so positioned that when the said eyepiece is directed

toward the face of a patient the observer will see the coordinated guide lines superimposed on an image of the patient's face, to give a direct reading of tooth width and length in millimeters by the observation of the width and height of the patient's face as viewed in superimposed relationship, and to emphasize the classification of the patient's facial shape.

7. A form selector and facial measurement device for denture prosthesis comprising a telescopic eyepiece, a transparency associated therewith, a means for maintaining an accurate predetermined spacing between the eyepiece and the face of the patient, and a means for indicating when the line of sight of the telescopic eyepiece is level; the said transparency carrying a series of coordinated guide lines calibrated in terms of tooth dimensions and so positioned that when the said eyepiece is directed toward the face of a patient the observer will see the coordinated guide lines superimposed on an image of the patient's face to give a direct reading of tooth width and length in millimeter by the observation of the width and height of the patient's face as viewed in superimposed relationship, and to emphasize the classification of the patient's facial shape.

8. A form selector and facial measurement device for denture prosthesis comprising a telescopic eyepiece, a transparency associated therewith, a means for maintaining an accurate predetermined spacing between the eyepiece and the face of the patient, and a means for indicating when the line of sight of the telescopic eyepiece is level; the said transparency carrying a series of parallel guide lines calibrated in terms of tooth dimensions and so positioned that when the said eyepiece is directed toward the face of a patient the observer will see the coordinated guide lines superimposed on an image of the patient's face to give a direct reading of tooth width and length in millimeter by the observation of the width and height of the patient's face as viewed in superimposed relationship, and to emphasize the classification of the patient's facial shape.

9. A facial measurement device for use in denture prosthesis, comprising in combination an optical eyepiece, a transparency carrying calibrated parallel guide lines thereon, and a spacing means on which the said eyepiece and the said transparency are assembled a predetermined distance apart and which is adapted to maintain the said eyepiece and said transparency at predetermined distances from a patient's face; in which the optical characteristics of the eyepiece, the calibration of the guide lines on the transparency and the distances between the patient's face, the transparency and the eyepiece are so coordinated that when the image of the patient's face is viewed through the transparent screen, the dimensions of a tooth suitable for that patient based on the accepted sixteen to one ratio between facial size and tooth size can be read directly on the calibrated scale of the transparency.
